UNITED STATES PATENT OFFICE.

BENJAMIN E. D. STAFFORD, OF PITTSBURGH, PENNSYLVANIA.

COLLAPSIBLE TUBE AND CONTAINER FOR THE SAME.

1,382,137.

Specification of Letters Patent. Patented June 21, 1921.

Application filed August 8, 1919. Serial No. 316,144.

To all whom it may concern:

Be it known that I, BENJAMIN E. D. STAFFORD, a citizen of the United States, and a resident of Pittsburgh, in the county of 5 Allegheny and State of Pennsylvania, have invented certain new and useful Improvements in Collapsible Tubes and Containers for the Same; and I do hereby declare the following to be a full, clear, and exact description of the invention, such as will enable others skilled in the art to which it 10 pertains to make and use the same.

My invention relates to an improvement in collapsible tube and container for the 15 same.

Many toilet and medical preparations are put up and sold in tubes which are made of flexible or compressible sheet metal, and are compressed to eject the contents from a nozzle provided thereon, and containers have 20 been provided for holding the tube, the contents being ejected by turning a slotted key applied to the end of the compressible tube. In all such instances however of which I am 25 aware, the containers have been designed to receive the ordinary flexible tube of commerce and in no instance has the container been designed to receive and coöperate with a specially designed collapsible tube.

30 My invention therefore consists broadly in a collapsible tube closed at one end and open at the other and a two part container the parts of which are adapted to engage the open end of the tube and secure it to the 35 container, the body of the container having a finger slot therein whereby the contents of the tube may be ejected by direct pressure of a finger against the same.

My invention further consists in the parts 40 and combinations of parts as will be more fully described and pointed out in the claims.

In the accompanying drawings; Figure 1 is a view partly in longitudinal section and 45 partly in elevation of a device embodying my invention; Fig. 2 is a similar view of a slightly modified construction; Fig. 3 is a view partly in section and partly in elevation of the collapsible tube shown in Fig. 1; 50 Figs. 4 to 10 inclusive are views of modified forms of tubes; Fig. 11 is a diagrammatic view showing the movement of the contents of the tube when pressure is applied to the closed elliptical end of the latter; 55 and Fig. 12 shows the shape assumed by the

elliptical end after the contents have been forced from the same.

15 represents the container closed at its lower end and open at its upper end, the upper end being thickened and screw 60 threaded as shown for the attachment of the head 16. The closed lower end 15^a of the container constitutes the base for supporting it in an upright position and this base is 65 preferably shaped to conform to the shape of the closed end of the collapsible tube 17. In Fig. 1 I have shown it curved to conform to the curved end of tube 17.

This tube 17 is cylindrical in shape and the body thereof is made of a flexible sheet 70 material preferably metal that will readily give under the pressure of the finger so that pressure applied against the outside of the tube will eject the contents thereof provided the discharge nozzle to be hereinafter referred to be open. It may however be made of rubber, and as illustrated in Fig. 10 I have shown a rubber tube circumferentially corrugated to produce ribs. The surface of the tube when made of rubber may be plain, or 80 roughened in any way.

This tube 17 is closed at its lower end and open at its other or upper end, the open end being thickened as shown and turned outwardly to form a flange 18. The enlargement 85 of the tube may be at the outside as shown in Figs. 1, 3, 4 and 6 or at the inside as in Figs. 2—7—8 and 9. Again this enlargement or thickening of the tube may be by a separate flanged reinforcing ring 18^a as 90 shown in Fig. 5 or by flanged rings within the open end of the tube as shown in Figs. 8 and 9. In all forms however the tube 17 is provided at its open end with an outwardly projecting flange 18 which overlaps 95 the open end of the container 15 and is clamped thereto by the head 16, the depending peripheral flange of which is internally threaded to engage the external threads at the upper end of the container. The head 100 is provided with a centrally located discharge nozzle 19 normally closed by a screw cap 20, and is provided internally with a flat annular shoulder 21 which rests on the flange 18 of the tube 17 and clamps it against the outer 105 end of the container, so that when the head is in place, the tube which may contain a fluid, paste or any other matter that can be ejected through the nozzle by pressure applied against the body of the tube, will be 110

in a position to discharge directly through the nozzle.

The container 15 is provided with a finger slot 22 for the insertion of a finger or fingers of the hand holding the container, so that the body of the tube may be directly engaged thereby and pressure sufficient applied to force the contents through the nozzle.

10 In Fig. 1 I have shown the closed end of the tube elliptical in shape and the base or end 15^a of the container made concave to conform to the end of the tube.

In Fig. 2, the tube is made with a lower 15 open end, as in Fig. 6, the said lower end being closed by flattening and folding as is done in the manufacture of the tubes now in common use: Instead however of making them in one continuous piece I may make the 20 closed end section separate and secure them together with their ends abutting as in Figs. 3 and 5 or overlapping as in Fig. 4. Where the tube is closed by flattening and folding as in Fig. 2, I prefer to make the end closure 25 15^b with an internal gutter to receive the flattened end to support the same when pressure is applied to the tube. In Figs. 5, 8 and 9 I have shown reinforcing bands secured to the open ends of the tubes and provided with the flange 18 by which the tube is 30 clamped in place.

When a tube is formed with a closed end I prefer to make the latter elliptical shape instead of semi-spherical for the reason that 35 with the latter, pressure near the closed end of the tube tends to cause the formation of a pocket which traps some of the material at the extreme end when the tube is deformed by finger pressure against the same, whereas 40 as with the elliptical end, pressure on the curved surface operates to expel the contents in the manner indicated by the dotted lines in Fig. 11 and when the finger pressure has forced the side of the tube with which the 45 finger is in contact against the opposite side, the movement will have pushed the contents of the end forwardly into the tube, thus expelling all and leaving the end curved as illustrated in Fig. 12.

50 The tube is susceptible of many changes both in construction and material hence I would have it understood that I do not confine myself to the details of any of the forms shown but consider myself at liberty to 55 make such changes as may come within the spirit of the invention above described.

Having fully described my invention what I claim as new and desire to secure by Letters-Patent is:—

60 1. The combination of a container open at one end and closed at the other end; externally threaded at its open end and provided with a finger slot in its body, a head screwed

to said open end and provided with a centrally located discharge nozzle normally 65 closed by a screw cap, and a collapsible tube housed within said container, the said tube being open at one end, the latter being thickened and flanged outwardly, the said thickened end of the tube forming a snug 70 fit with the container at the open end of the latter, and the flange on said tube overlapping the free end of the container and clamped thereto by the head bearing against the flange. 75

2. The combination of a container having a finger slot in its side and open at one end and closed at the other, its open end being thickened and screw threaded externally, a head having a depending flange internally 80 threaded to engage the external threads on the container and also provided with a centrally located discharge nozzle, and a collapsible tube housed within said container, the said tube being open at one end and 85 closed at the other, the open end being thickened and flanged outwardly, the thickened end of the tube forming a snug fit with the thickened end of the container and the flange on the tube resting on the outer open end of 90 said container and clamped thereto by the head.

3. The combination of a container open at one end and closed at the other end; externally threaded at its open end and provided 95 with a finger slot in its body; a head screwed to said open end and provided with a centrally located discharge nozzle normally closed by a screw cap and a collapsible tube housed within the container, the said tube 100 being reinforced and open at one end, the latter being flanged outwardly, the said open end of the tube forming a snug fit with the container at the open end of the latter, and the flange on said tube overlapping the open 105 end of the container and clamped thereto by the head contacting with the flange.

4. The combination of a container closed at one end and open at the other end and having a finger slot in its side, a collapsible 110 tube within the container the said tube being open at one end and closed at the other and provided with a reinforcing flanged band at its open end, the flange on said band adapted to engage a seat on the container, 115 and a head for closing the open end of the container and for clamping the tube in place, the said head having a discharge nozzle closed by a cap.

In testimony whereof I have signed this 120 specification in the presence of two subscribing witnesses.

BENJAMIN E. D. STAFFORD.
